CIRCULAR RAMP FOR GARAGES AND THE LIKE

George Gore, San Francisco, Calif., assignor of one-half to Ferd W. Callison, San Francisco, Calif.

Application March 15, 1955, Serial No. 494,424

1 Claim. (Cl. 20—1.13)

This invention relates to improvements in garage construction and parking arrangements.

The principal object of this invention is to provide a self-parking garage which can accommodate a large number of cars on various floors through the use of a circular ramp having a low grade, together with a floor arrangement associated with each ramp level to provide self-parking with a minimum amount of effort on the part of a driver, as well as to insure a steady flow of traffic over the floors and to the downramps, without interference from up-coming vehicles.

A further object is to provide a structure which may be easily accommodated to various lot sizes by rotating the axial arrangement of the ramps to the specific floor plan determined by the building shape.

A further object is to produce a garage of the character described which may be erected with a minimum amount of construction and costs incident thereto.

Other objects and advantages will be apparent during the course of the following description.

In the accompanying drawings forming a part of this specification and in which like numbers are employed to designate like parts throughout the same:

Fig. 1 is a plan view of a typical ground floor of a building into which vehicles enter;

Fig. 2 is a plan view of a typical elevated floor;

Fig. 3 is a side elevation of a garage building having my invention applied thereto; and

Fig. 4 is a fragmentary enlarged cross sectional view showing the ramps between two of the floors.

Heretofore garages as ordinarily constructed have been conventional buildings, some with ramps for driving the vehicles from one floor to the next, some with elevators, and other of an automatic type where the cars are placed upon a certain area, elevated to a certain floor level and then transported to a particular stall and driven into the stall off of the elevator.

Applicant has found that these types of garages are inefficient, that they cause long delays in storing and returning vehicles to customers, due to the fact they are not suited for self-parking.

Also, these types of buildings require a large number of employees causing prohibitive rate for parking, with resultant street parking and frequent movement of cars from parking meter to parking meter, as well as the effort of moving the cars and the loss of time incident thereto.

Applicant has therefore devised a garage wherein at some portion of the building, and preferably adjacent one corner thereof, is located a series of vertically arranged ramps which, together with their associated floors, form a continuous circular path from the bottom to the top floor of said building. By an ingenious arrangement these ramps will carry both up and down traffic and, also, both up and down traffic will travel in the same direction, thus eliminating any confusion on the part of a driver through seeing another car coming in the opposite direc-

2

tion on the adjacent ramp, and thus avoiding accidents that might otherwise occur.

Each ramp is so designed that it extends around the central pylon substantially one-third of the distance of 5 a complete revolution. The remaining portion of the revolution is on a level floor before starting up the next ramp to the floor above.

This arrangement produces a very low grade with comparatively low ceilings, with a resulting larger number 10 of floors to a given height than in ordinary building construction.

Also, by having a large portion of the circular path on the level, a driver is enabled to veer off into any particular parking space as directed by a garage attendant, and 15 also enables a person driving off of a floor and on to a down ramp to have plenty of room to maneuver.

In the accompanying drawings, wherein for the purpose of illustration is shown a preferred embodiment of my invention, and referring to Fig. 1 in particular, the 20 numeral 5 designates the ground floor, and the numeral 6 designates supporting columns for the floors above. At 7 I have shown a entrance lobby and at 8 cashier desks, the purpose of which will be later seen.

Elevators are shown at 9. 25 At one corner of the building I have positioned a pylon 11 around which are positioned a plurality of supports 12 arranged substantially in a circle, these supports 12, together with the pylon 11, serving to support curved ramp sections 13 and 14 as best shown in Fig. 4.

30 The up ramp 13 fairs into, for instance, the second floor, and goes through substantially a third of a revolution, and has its upper end fairing into the third floor structure.

The ramp 14, being a down ramp, has its beginning 35 end level or fared into the third floor and also rotates a third of a revolution and fairs into the second floor.

Consequently two cars moving simultaneously on ramps 13 and 14 will be going in the same direction and therefore will not interfere with each other and will pass out 40 of each other's view after a short interval of running abreast as the car on ramp 13 is moving upwardly at the same time that the car on ramp 14 is going downwardly.

By referring to Fig. 1, the arrow A designates a car 45 coming off of the street and going along a path indicated by dotted lines for gasoline service or the like; a car entering as indicated by the arrow B will be in alignment with the beginning of the up ramp 13 going up from the ground floor to the second floor. Cars can also enter as shown by the arrow C and follow the dotted line course around to the course shown by the arrow B.

Cars entering the garage will pass an attendant located in the area 16, where the drivers will receive parking tags and duplicate stubs will be placed upon the vehicles.

The tag that a driver receives will be time marked. 55 The driver then proceeds upwardly to a designated floor, for instance, the second floor, as shown in Fig. 2, and will then follow the arrow D and into one of the parking stalls E or F, as the case may be.

When all of the stalls on the upper portion of the figure 60 have been filled, then an attendant, who is located at the point 17, will direct traffic as shown by the dot and dash line arrow H, and the drivers will then park in the stalls I or J.

At the end of the parking period, a person calling for 65 his car will enter the lobby 7, present his claim tag to one of the cashiers, pay the amount due, and then take an elevator to the designated floor where his car has been parked. After getting into his car the person will back out and follow the dotted line indicated by the arrow G past the attendant at 17, where he will relinquish the 70 claim check, and move off of the downramp and out of the building.

It is of course understood that there will be garage attendants on each floor to direct parking and unparking of cars therefrom. However, the number of attendants required will be greatly reduced due to the self-parking arrangement.

It is obvious that by rotating the entrance and exit points of the various ramps, the same can be accommodated to fit in with whatever floor plan might best be suited for any particular shape of building area.

It will thus be seen that my arrangement accomplishes all of the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having described my invention, I claim:

In a storage building for parking automobiles and the like, the combination of a plurality of floors, each of which is divided into lines of individual parking areas, with said lines of parking areas opening into traffic flow lanes, a dual concentrically positioned adjacent series of

arcuate up and down traffic ramps interconnecting successive floors with each other, said ramps also being located at one side of and at the extreme end of each of said floors, each of said series of ramps forming in conjunction with all of the said floors a continuous winding passageway between the adjacent floors, one of said series of ramps being used by automobiles moving in an upward direction and the other of said series of ramps being used by automobiles moving in a downward direction, the entrance and exit ends of each arcuate ramp facing in the general direction of the traffic flow lanes, said traffic flow lanes comprising at least three lanes, the outer two of which form feeder lanes from an upcoming ramp to the middle lane, said middle lane terminating 15 in proximity of the entrance to a down ramp.
